UNITED STATES PATENT OFFICE.

GEORGE H. ELLIS, OF ST. PAUL, MINNESOTA.

COMPOSITE LATH AND HEAT-INSULATING MATERIAL.

1,126,186.

Specification of Letters Patent.

Patented Jan. 26, 1915.

Application filed May 9, 1914. Serial No. 837,555.

To all whom it may concern:

Be it known that I, GEORGE H. ELLIS, a citizen of the United States, residing at St. Paul, in the county of Ramsey and State of Minnesota, have invented certain new and useful Improvements in Composite Lath and Heat-Insulating Material; and I do hereby declare the following to be a full, clear, and exact description of the invention, such as will enable others skilled in the art to which it appertains to make and use the same.

My present invention has for its object to provide an improved composite lath and heat insulating building material, and to such ends, generally stated, the invention consists of the novel devices and combinations of devices hereinafter described and defined in the claims.

The body of this improved material is preferably a felted sheet of insulating fiber, such for example, as that disclosed and claimed in United States Patent No. 908,681, granted to James E. Lappen, of date, January 5th, 1909, and entitled Flax felt, but such insulating material may take various other forms, so far as the broad idea of this invention is concerned. For example, this heat insulating sheet might be composed of shredded straw, corn stalks, hemp, or even "excelsior" shavings. However, felted flax or hemp make the best material for the above noted purpose.

On the outer face of the insulating sheet or body is placed a sheet of water proof material, such as a cheap grade of roofing or some of the better grades of building paper. A heavy water proof paper known under the trade name of "Neponxit" paper affords a very good material for this purpose. The lath are preferably provided with beveled edges and they are suitably secured on the water proof facing sheet and are secured to the main body sheet of insulating material, preferably by staples or small nails. The beveled edges of the lath afford dove-tailed channels between the lath which is well adapted to hold the plaster in position.

The invention is illustrated in the single view of drawing, which is a perspective view, partly in section and with some parts broken away.

The felted body of insulating material is indicated by the numeral 1, the water proof

facing by the numeral 2, and the lath by the numeral 3.

The numeral 4 indicates staples driven through the insulating sheet 1 and water proof sheet 2 and into the lath.

The numeral 5 indicates the body of plaster which is applied to the lath and against the water proof sheet.

This improved building material is adapted to be used both inside and outside of the walls of buildings and it is well adapted to take the place not only of sheathing boards but also of the ordinary expanding material or wire lath. In fact, the wooden lath will last longer than the metal lath and the insulating body is a much more efficient heat insulator than sheathing boards, even when the latter are combined with many layers of ordinary building paper. In fact, experience has shown that this material is well adapted for use both as a heat insulator and lath, when applied directly to the studding of buildings for the application of the external coat of plaster, cement or stucco. It is well known that the large number of air cells in felted fiber sheets give the same a very high heat insulating quality. The water proof facing sheet is, of course, very desirable because it positively keeps moisture out of contact with the insulating material and prevents rotting or souring thereof, and furthermore, this facing sheet is also a good heat insulator and effectually resists the passage of air through the material.

The felted fibrous insulating body sheet, while it has sufficient rigidity to maintain its own form under ordinary handling, is, nevertheless, quite flexible and may be easily bent in a curved or other form in a direction transversely of the lath. In the direction of the lath, the composite material is stiff so that it is well adapted to span the space between studding and to be nailed directly thereto.

What I claim is:

1. A composite lath and heat insulating material comprising a felted insulated body sheet, a water proof facing applied thereto, lath applied to said water proof facing, and metallic fastening devices driven through the said three elements to securely fasten said lath to the said felted body sheet and to the said facing.

2. A composite lath and heat insulating

material comprising a felted insulated body sheet; a water proof sheet applied thereto, and lath applied to said water proof sheet, the said three elements being secured together by means of staples driven through said insulating sheet and water proof sheet and into said lath.

3. A composite lath and heat insulating material comprising a felted insulated body sheet, a water proof sheet applied thereto, and lath applied to said water proof sheet,

the said three elements being secured together, the edges of the said lath being beveled to afford dove-tailed channels between the lath.

In testimony whereof I affix my signature in presence of two witnesses.

GEORGE H. ELLIS.
